UNITED STATES PATENT OFFICE.

BISUTTI PIETRO FU NATALE, OF PORDENONE, ITALY.

CEMENT-MOLDING APPARATUS.

Application filed May 21, 1926. Serial No. 110,687.

This invention relates to cement molding apparatus.

Objects of this invention are to provide a cement molding apparatus which may be used to form pillows or posts either of solid construction or with a hollow center.

Further objects are to provide an apparatus for molding cement to form pillows which are so constructed that both the body portion and the core may be extended or contracted as desired, and in which these parts are so made that they may be opened up to receive additional plates to thus increase their size and to provide effective means for holding the composite body portion and core of the device rigidly in assembled position.

Further objects are to provide a cement molding device which is very simple and may be cheaply and readily produced, and which is easy to handle.

Embodiments of the invention are shown in the accompanying drawings, in which:

Figure 1 is a plan view of the device.
Figure 2 is a sectional view approximately on the line 2—2 of Figure 1.

Figure 3 is a sectional view approximately on the line 3—3 of Figure 1.

Figure 4 is an elevation of a corner portion of the device when it is modified to form a different type of pillow.

Figure 5 is a sectional view on the line 5—5 of Figure 4.

Referring to the drawings, it will be seen that the device comprises a main body portion and a core portion. The body portion is formed of four corner members 1 which are of plate or sheet metal. These corner members are each provided with U-shaped guides or clips 2 which are apertured and are adapted to receive tapered pins 3. The guides 2 receive straps or bars 4 which are located outside of the main portion of the device, as shown in Figure 1, and are locked to the respective corner portion by means of the pins 3, when such pins are driven downwardly into binding engagement. These corner portions 1 are each provided with pairs of ears 5, one pair of which is very clearly shown in Figure 2. These ears are arranged on the outer side of the corner members 1 and are adapted to engage the outer face of the extension plates 6, such extension plates being positioned between the corner members. These extension plates are similarly provided with pairs of ears 7.

The ears are so arranged that they interlap, one within the other, as indicated in Figure 2, and this scheme is followed throughout the entire device. It will be seen, therefore, that by the arrangement of the ears carried by the plates and by the corner members, such plates are rigidly held against motion either inwardly or outwardly.

After the desired adjustment or size of the member has been secured, the corner members are pressed closely into engagement with the plates, and the pins 3 are driven into place, thus locking the bars or straps 4 tightly to the corner members and holding the parts of the body portion or outer portion of the device rigidly in assembled position.

It is to be noted that the bars 4 are provided with apertures 8 adjacent their ends by means of which they may be bolted to other similar bars to thus permit a greater extension of the body portion.

Referring now to the core portion of the device, it will be seen that such core portion is formed of corner members 9, and that these corner members are adapted to receive extension plates 10 between them. The corner members 9 are provided with pairs of ears 11, and the extension plates 10 are similarly provided with pairs of ears 12, as most clearly shown in Figure 2. Thus the core portion of the apparatus may be extended in a manner similar to the body portion.

Other means, however, are employed for holding the core portion in its assembled position, and such means comprise spaced plates 13 (see Figure 3) which receive between them a slotted tongue 14. This tongue is drawn inwardly by means of the tapered pin or wedge 15. The outer end of the tongue carries a chain 16 which is adapted to be hooked over the hook 17, a plate 18 carried by the diagonally opposite corner portion (see Figures 1 and 3). In other words, two of the corner portions carry the spaced plates and the other two carry the single plates provided with hooks.

In adjusting this core portion, the requisite size of number of spacing plates 10 are positioned and the chains are passed over the hook 17 at the approximate adjustment required. Thereafter, the wedges or pins 15 are driven into place, thus, drawing the chains tight and holding the core portion rigidly locked and braced.

As shown in Figure 1, it may be desirable to provide cut away portions for the corners of the cores. This is readily secured by shaping the corner members 9 as shown in Figure 1. Obviously, other shapes could be employed.

If it is desired to provide a post with cut away corners, it is merely necessary to employ the construction shown in Figures 4 and 5. In these figures, the corner members 1 of the main member carry traverse plates 19 which are provided with ears 20 adapted to be passed through corresponding apertures 21 formed in the corner portion 1. Thereafter, pins 22 are passed through apertures formed in the ears 20 to thus lock the plates 19 in position.

It is, of course, to be understood that although the body portion of the device and the core have been shown as adjusted for approximately square sections, it is clear that they may be adjusted for other rectangular sections by the proper selection of spacing plates.

It is also clear that any number of these spacing plates may be used, or that the spacing plates may be of different sizes although it is preferable to have a large number of spacing plates so that the device may be built up as desired.

It will be seen that a very simple and serviceable type of molding device for cement has been provided which may be rapidly used to form posts either hollow or solid. Further, it is to be noted that the side bars 4 form efficient handles for lifting the mold out of place. Further, the core may be readily removed by grasping the chains 16 and sliding the core upwardly.

It is to be noted also that the device is rugged and can not be readily damaged. When it is appreciated that these devices are subjected to great abuse in the ordinary service in which they are used, it is clear that this feature is highly desirable.

Further, it will be seen that the device may be very cheaply manufactured as it is relatively simple, and that it is composed of a relatively small number of parts.

Although the invention has been described in considerable detail, such description is intended as illustrative rather than limiting as the invention may be variously embodied and as the scope of such invention is to be determined as claimed.

I claim:

1. A cement molding apparatus comprising an outer body member and an inner core member, said outer body member and said inner core member each having corner portions, and intermediate plates between said corner portions, said plates and said corner

portions each having a series of ears for holding such portions in relative position, and means for locking the corner portions against outward separation.

2. In a cement molding apparatus, the combination of a plurality of corner members having guides thereon, bars passing through said guides and extending from one corner member to the next corner member, intermediate plates located between said corner members, and means for locking said guides to said bars.

3. In a cement molding apparatus, the combination of corner members, U-shaped guides rigidly carried by said corner members and projecting outwardly therefrom, bars passing through said U-shaped guides, means for frictionally locking said bars to said guides, intermediate plates positioned between said corner members, and tongues carried by said plates and said corner members for holding said plates in position.

4. In a cement molding apparatus, the combination of corner members, U-shaped guides rigidly carried by said corner members and projecting outwardly therefrom, bars passing through said U-shaped guides, said guides having apertures therethrough, tapered pins passing through said apertures for locking said guides to said bars, intermediate plates positioned between said corner members, and tongues carried by said plates and said corner members for holding said plates in position.

5. In a cement molding apparatus, the combination of corner members, chains extending diagonally from one corner member to the other, intermediate plates located between said corner members, and means for tensioning said chains, while said intermediate members remain stationary.

6. In a cement molding apparatus, the combination of four corner members, two of said corner members having spaced plates provided with apertures with the diagonally opposed corner members having plates provided with hooks, chains carried by said hooks and extending diagonally towards the corresponding pair of spaced plates, a slotted plate carried by the free end of each of said chains and located between said spaced plates, wedges passing through said spaced plates and said slotted plates for tensioning said chains, said corner members being spaced apart, removable intermediate plates located between said corner members, and means for holding said intermediate plates against lateral displacement.

In testimony that I claim the foregoing I have hereunto set my hand at Milan, Italy.

BISUTTI PIETRO FU NATALE.
